UNITED STATES PATENT OFFICE.

JAMES H. FOOTE, OF CINCINNATI, OHIO.

WEATHER STRIP.

Application filed January 19, 1924. Serial No. 637,339.

My invention relates to improvements on weather strips. One of its objects is to provide an improved sheet metal weather strip adapted to be applied to windows, doors, and similar openings where it is important to exclude the passage of water and cold air at the joints during cold and wet weather. Another object is to provide an improved all metal weatherstrip adapted to more perfectly close the joints and exclude rain and cold air. Another object is to provide an improved weather strip adapted by its outline, shape and relation of parts to more perfectly and persistently retain its original outline and to thereby more perfectly perform its function and for longer periods of time, and to more perfectly meet the varying conditions of practical application. My invention also comprises certain details of form and combination of components, all of which will be fully set forth in the description of the accompanying drawings, in which:

Fig. 1 is a perspective view of a section of sheet metal weather strip embodying my invention.

Fig. 2 is a horizontal section through one side of a window frame and sash illustrating the application of my improved weather strip thereto.

Fig. 3 is a horizontal sectional detail through one side of a door frame and door illustrating the application of my improved weather strip thereto.

Figs. 4 and 5 are sectional details illustrating the range application of my improved weather strip.

The accompanying drawings illustrate the preferred embodiment of my invention in which the weather strip is formed by bending or folding upon itself a relatively narrow strip, of resilient sheet metal or other resilient material longitudinally thereof along a line 20. The line 20 is preferably so located with reference to the width of the strip that a relatively narrow leaf or blade 22 is preferably bent outwardly from the base sections 21 along the line 40 and is adapted to bear yieldingly against one face of the joint, say against the face 24 of the window frame 25. In Fig. 2 a relatively wider leaf or blade 26 is adapted to bear yieldingly against the opposite face of the joint, say against the face 27 of the window sash 28.

In order that the leaf 26 may be better

adapted to retain its shape, and also that it may engage more perfectly and satisfactorily with the joint to be closed, and in order that it may more perfectly engage and disengage with the joint to be closed where such action is required, said leaf 26 is curved transversely of its length into substantially a section of a cylindrical body, and at its free end 30 is preferably turned upon itself to provide a smooth binding or finished edge adapted to slide freely along either face of the joint to be closed, without liability to catch or bind thereon. Thus where the joint to be closed is narrow the middle section of the curved leaf 26 is adapted to engage firmly against one face of the joint, say the face 27 of Fig. 2, while the two opposite edges 30 and 31 of said curved leaf both tend to react against the pressure on the joint face 27 and to press against the joint face 24 to doubly and more effectually close the joint between the sash and window frame. Substantially the same action will be had to close the joint between a door and door frame as shown in Fig. 3 for instance:

The base member 21 serves as a point of attachment for the weather strip, which is preferably effected by means of screws or nails 23 passing through perforations in the base member 21 at intervals and into the window frame or door frame. Normally the spring action of the leaf 22 is to lift the base of the leaf 22 along line 40, and also the base of the leaf 26 at 31 away from the face of the joint to which the base member 21 is attached by the screws 23 and thereby affords a more resilient bearing or contact of the leaf members 22 and 26 against the opposite joint surfaces, and thereby affords a more effective and perfect weather protection than would be otherwise attainable.

Where, however, the joint to be closed is relatively wide, as shown for instance at Fig. 5, a portion of the curved face of leaf 26 will bear against one joint face 32 and the base of the leaf 26 at 31 will bear indirectly against the joint face 33, while the end 30 of the leaf 26 will remain out of contact with the joint face 33. The curved outline of the leaf 26, as indicated in Fig. 3, tends to more readily make and break the joint between the free or moving edge or face 35 of a door and the face 36 of the jamb of the door frame 37, substantially as above described, to secure either a single or double engagement of the leaf 26

with the joint faces, depending upon the width of joint to be closed thereby. The weather strip Fig. 3 is preferably attached by screws or nails 23 to the face 36 of the 5 jamb. In Fig. 2 I have shown the weather strip attached by screws or nails 23 to the window frame, but it may, if desired, be attached to the window sash.

The curved or cylindrical outline of the 10 leaf 26 enables said leaf to selectively make contact at different points along its curved face, and tends to prevent dents being formed in the face thereof, and tends to secure a more uniform and continuous engagement of said leaf with one or both of the 15 faces of the joint to be closed even though the joint should be wider at one end than at the other. The mutual action of the two diverging resilient leaves 22 and 26 and their 20 uniting and attaching member is such that said members do not lose their resiliency in use, even under severe and repeated pressure or strain, and hence retain and return to their original position when strain thereon 25 is released. The positions of the strip in Figs. 4 and 5 indicate approximately opposite extremes of the range of adjustment required in practice. Often the strips are flexed through the full range from that 30 shown in Fig. 5 to that shown in Fig. 4 in the operation of a single sash, and it is important that the resiliency be repeatedly fully recovered.

The apparatus herein shown and described 23 is capable of considerable modification within the scope of the claims without departing from the spirit of my invention.

What I claim is:

1. A weather strip comprising a strip of 20 resilient material folded longitudinally thereof upon itself to form near said bend a section of double thick material to be attached to one of the joint members, a relatively narrow leaf normally at an obtuse angle relative to said double thick section to contact resiliently with one joint face, and a relatively wide leaf extending relative to said double thick section in a direction divergingly opposite to that of 25 said narrow leaf and curved transversely of its length to resiliently engage with some portion of said curved face continuously along an opposite joint face.

2. A weather strip comprising a strip of 30 resilient material folded longitudinally thereof upon itself to form a section of double thick material to be attached to one of the joint members, a relatively narrow

leaf normally extending at an obtuse angle 35 relative to said double thick section in a direction to contact resiliently with one joint face, and a relatively wide leaf extending relative to said double thick section in a direction divergingly opposite to that of said narrow leaf, said wider leaf being curved 40 transversely of its length and having its free edge folded upon itself to provide a rounded edge, said curved leaf being when applied to relatively narrow joints adapted to engage at both edges with one joint 45 face and to engage at an intermediate portion of its curved face with an opposite joint face.

3. A weather strip comprising a strip of 50 resilient material folded longitudinally thereof upon itself to form a double thick section to serve as a point of attachment and to provide two spring leaves diverging from one edge of said double thick section, one of said diverging sections being curved 55 transversely to its length and having its free edge folded over upon itself to constitute a smooth edge adapted to glide over one of the joint faces when said curved leaf is placed under tension between the joint 60 faces.

4. A weather strip comprising a strip of 65 resilient material folded longitudinally thereof upon itself to form an attachment member and to provide a pair of leaves diverging from said double thick section, one of which leaves is curved transversely to the 70 length of the strip, and which leaves 75 fulcrum at a common point along the margin of said double thick section and are adapted to bear resiliently upon the opposite walls 80 of the joint to be closed.

5. A weather strip comprising an attachment member of double thickness of material, an outwardly inclined plane resilient 85 leaf extending at an obtuse angle from one edge of said double thick attachment member and adapted to resiliently engage the face of one of the joint members, and an 90 outwardly and oppositely inclined leaf 95 curved in cross-section extending from the same edge of said double thick attachment member and adapted to resiliently engage the face of the opposite joint member, the junction between the base of said leaves and 100 said double thick attachment member being 105 resiliently held out of contact with the faces of both of said joint members.

In testimony whereof, I have hereunto set my signature.

JAMES H. FOOTE.
